LUMINOUS SIGN

Harry R. Van Deventer and John J. Shively, New York, N. Y., assignors to Neosign Corporation, a corporation of Delaware

Application April 30, 1935, Serial No. 19,039

14 Claims. (Cl. 40—132)

This invention relates to improvements in a luminous sign and more particularly to a sign of such construction that it is easily combined with other devices such as cash registers, gasoline and oil pumps, scales, coffee mills, meat slicers and the like.

An object of the invention is to provide a sign adapted to employ a grid of luminous tubing and to resiliently mount same in the sign 10 casing.

Another object is to provide a sign having an outer and inner glass and means between said glasses whereby the indicia of the sign can be changed.

15 A further object is to provide a sign to be combined with and if desired actuated by the operation of another device on which the sign is supported.

Other objects will appear from a perusal of 20 the following specification, wherein one form of the sign is disclosed, adapted to be mounted on a cash register. This disclosure is however merely for the sake of illustration and the invention is not to be considered as limited thereto.

25 In the accompanying drawing:

Figure 1 is a perspective view of a sign combined with a cash register and embodying the invention;

30 Figures 2 and 3 are detail views of the drawer switch mechanism shown in Figure 1;

Figure 4 is a cross-sectional view of the sign, Figure 1;

35 Figure 5 is an enlarged view of the grid and reflector shown in Figure 4; and

Figure 6 is a side view of a combined sign and cash register showing a modified transformer and switch arrangement.

One of the principal objects of the invention 40 is to provide a sign which may be combined with a device such as a cash register, gasoline or oil pumps, scales, coffee mills or any other devices commonly used in stores. If desired, the sign can be so arranged as to be displayed 45 at the manual operation of some part of the device on which it is mounted.

For the sake of illustration, the sign has been 50 shown in Figure 1 mounted upon an ordinary cash register, and the numeral 10 denotes the body of the register, and the numeral 11 denotes the sign proper mounted thereon and wholly supported thereby.

The luminous tube 36, hereinafter described 55 in detail, is connected to the transformer 12 by

means of the high tension leads 13 which are covered by an insulating tube 14.

The main switch 15 is connected to the auxiliary switch 16 by means of a shunt connection 17, switch 16 controlling a flasher 18 and said 5 switch being controlled by a button 19 which extends through the side wall of the register. By means of this button, the switch can be turned on and off in order to control the flasher circuit.

10 A low tension lead such as an ordinary flexible cord 20 is provided with a plug 21 which may be inserted in any convenient electric outlet.

The main switch 15 is provided with a plunger 22 which has a spring 23 around the shank 15 thereof which keeps the plunger in a normally extended position as shown in Figure 2. This plunger is under the control of the drawer 24 of the cash register. These drawers are usually so constructed that upon pushing one of 20 the keys 25 of the register, the drawer is released and springs outwardly from the position shown in Figure 3 to that shown in Figure 2, thereby controlling the switch 15 which is in its "off" position when the plunger 22 is in the 25 position shown in Figure 3, and "on" when the plunger is out as shown in Figure 2; or obviously the "on" and "off" positions can be reversed.

From the foregoing, it will be evident that the circuit from the plug 21 through the cord 20 and 30 through the switches 15 or 16 and via transformer 12 to the luminous tube 26 is controlled by the movement of a part of the device on which the sign 11 is supported, and it will be obvious that this control could be effected not 35 only by the drawer 25 but also by the depression of one of the keys 25.

It will also be understood that the control of a sign can be effected by other means when it is mounted on a device, for example, such as a 40 gasoline pump commonly used at filling stations. Here the movement of the hose would control the sign by means of a switch of any suitable construction, replacing the drawer 24 in this respect.

45 In the case of coffee mills or the like on which the sign 11 may be mounted, it is obvious that it can be controlled by any suitable switching mechanism adapted to be controlled in unison with the switch for starting and stopping the 50 motor of the device. Such switching arrangements are entirely within the skill of a competent engineer and do not require illustration here, it being sufficient for the purposes of this application to disclose the broad idea of a lu- 55

minous tube sign in combination with a switch, the latter being controlled by some moving part of the apparatus or device on which the sign is supported.

5 In use on any device, the sign cooperates therewith to call attention to the merchandise handled by the device, or to convey some message in respect to the sale or other transaction registered thereby.

10 For example in connection with the cash register shown in Figure 1, upon depressing one of the keys 25 and thereby releasing the drawer 24, switch 15 is operated, a circuit is established through the transformer to the luminous tube 36 which lights, thereby displaying a sign on the transparency 35 to be presently described. This sign may consist of the words "Thank you" or it may convey any other sales message desired. In the type of registers where there are separate keys 25 for each salesman or each department, it is possible to have the transparency 35 so arranged that only a part thereof is illuminated representing a certain department. For example, suppose the indicator 26 in the register 15 window 27 is displayed in connection with the purchase of gloves by reason of the fact that all gloves are handled by salesman "A" who depresses the "A" salesman's key in the register when making a sale. Then simultaneously with the 20 appearance of the registry number such as 26 in the window 27 of the register, the sign 11 will be illuminated across a portion of the transparency 35, which portion may read "The gloves you have just purchased are fully guaranteed."

If the purchase were stockings sold by salesman "B" then upon depression of the "B" key, the message illuminated on the transparency would be appropriate to stockings, etc.

40 The sign provided as shown in Figure 4, comprises a body or frame 28 preferably of insulating material having an inwardly extending flange 28a the rear side of which flange supports a transparent panel 29 of suitable material such as glass or the like, which is preferably held to the flange 28a by means of cement as shown at 30. This glass may carry the indicia to form a sign.

An outer transparent panel of glass or the like 50 31 is mounted in the outer frame 32 which is provided with a suitable gasket 33 of soft rubber or the like.

The frame 28 is provided with a downwardly extending outer lip 34 around the top outer edge thereof, and it will be apparent from a study of 55 Figure 4 that the frame 32 carrying the outer glass 31 is readily removable from the main frame 28 and that when placed therein in the position shown in the figure, a space exists between the inner and outer glasses.

In the space just mentioned (when the glass 29 is left blank) may be placed a transparency 35 which transparency may be of any suitable form such as a piece of cellophane, celluloid, glass or any other transparent or translucent material having a solid black background with the letters or other design forming the sign transparent or translucent so that the light from the luminous tube 36 may find egress there-through.

70 The luminous tube 36 may be of any suitable type, preferably of the gaseous type such as the well known neon type and this tube rests against the inner surface of the inner glass 29 and behind the tube is placed a plurality of

reflector strips 37 behind which strips is placed the soft ordinary sponge rubber support 38 which support in turn is carried by the braces 39 forming part of the back 40 preferably of insulating material which back is secured by 5 any suitable means such as the screws 41 to the body 28.

Suitable high tension leads like those shown at 13, Figure 1, connect the terminals of the tube 36 with the secondary winding of the 10 transformer 12.

In some cases where it is desired to have the transformer directly associated with the luminous tube in the sign, the arrangement shown in Figure 6 may be employed. Here a register 42 15 or other device on which the sign is to be mounted, carries the sign 47 thereon as shown, the back 40 having a rearwardly extending portion 48 in which the transformer is located.

A conduit 46 may convey the low tension or 20 primary current to the transformer and this conduit may terminate in the switch 43 having an arm 44 extending therefrom adapted to be moved by the opening and closing of the register drawer 24 in order to control the sign. Connection is made to the electric circuit via the cord 45 and plug 21.

It will be observed that in connection with either of the signs shown in Figures 1 and 6, that the position of the sign may be reversed 30 so that the face thereof can be turned either outwardly as shown or inwardly towards the keys 25. It will also be evident that when the sign is built into a device such as the register shown in the figures, that the transformer 12 35 may be located either on the base of the register frame inside the casing thereof or in any other suitable location; that the main distinction between the method of mounting as shown in Figures 1 and 6 is that in Figure 1 the transformer is mounted on the device supporting the sign. In Figure 6, the transformer is mounted upon the sign proper.

The body, frame or front casing 28 and back casing 40, Figure 4, and the corresponding front 45 and back casings on the sign 47, Figure 6, are preferably made of insulating material such as bakelite or the like, so as to enclose all of the parts of the sign that might come in contact with the circuits thereof.

50 It will also be observed that the sign proper can be detached from the device on which it is mounted without disturbing any parts of the said device, the sign body 28 being entirely separate and independent from the body 10 of 55 the device on which the sign is mounted.

Although the invention has been disclosed in connection with the specific details of preferred embodiments thereof, it must be understood that such details are not intended to be limitative of 60 the invention except in so far as set forth in the accompanying claims.

What is claimed is:

1. In a sign, a body having an inwardly extending flange, a transparent member resting 65 against the inner surface of said flange, illuminating means adjacent the rear surface of said member, a reflector in the rear of said means, a rear casing and resilient means supported on said casing for positioning said illuminating 70 means and reflector relative to said member.

2. In a sign, a body having an inwardly extending flange, a transparent member resting against the rear surface of said flange, illuminating means adjacent the rear surface of said 75

- member, a reflector in the rear of said means, a rear casing secured to said body on which said means and reflector are supported, a second transparent member supported by said body in 5 front of said first member, and means forming a sign adapted to be illuminated by said first means positioned between said members.
3. In a sign, a body, a transparent member supported therein, illuminating means in the 10 rear of said member, a reflector in the rear of said means, a rear casing secured to said body and supporting said means and reflector in operative relation thereto, a second transparent member removably positioned in said body, and 15 means forming a sign positioned between said members.
4. The sign as claimed in claim 3, wherein the second transparent member is provided with a frame removably mounted in the body.
- 20 5. The sign as claimed in claim 3, wherein the second transparent member is provided with a frame removably mounted in said body, a gasket being interposed between said body and frame whereby egress of moisture to the space 25 between the transparent members is prevented.
6. In a sign, a body, a transparent member supported therein, illuminating means in the rear of said member, a reflector in the rear of said means, a rear casing secured to said body 30 and supporting said means and reflector in operative relation thereto, a second transparent member removably positioned in said body, means forming a sign positioned between said members, and a transformer supported in said 35 body and having connections to said illuminating means.
7. In a sign, a body, a transparent member supported therein, illuminating means comprising a tube having a plurality of substantially 40 parallel portions, a reflector in the rear of said tube comprised of a plurality of individual strips lying substantially parallel with said tubes, a resilient support for said reflectors adapted to hold same in contact with the rear of said tube 45 and to press the latter against the inner wall of said transparent member, a rear casing adapted to support said resilient means, and a transformer connected to said tube and supported by said casing.
- 50 8. In a sign, the combination of a body, a transparent member supported therein, a luminous tube grid adjacent the inner face of said member, a reflector positioned behind said grid, a resilient support for said reflector, and a rear casing adapted to enclose said member,
- grid and reflector, said casing having an inwardly extending portion adapted to support said resilient means.
9. In a sign of the class described, a body comprising a frame having an inwardly extending flange, a glass supported on the inside of said flange, a luminous tube behind said glass, a frame removably supported in said body and adapted to engage said flange on the outer side thereof, a glass in said frame spaced apart from 10 said front glass, and a transparency between said glasses.
10. A sign as claimed in claim 9 having a rear casing secured to the frame, said rear casing enclosing and supporting a transformer connected to the luminous tube.
11. In a sign, a frame having a transparent front fixed therein, a second frame removably fitting within said first frame and having a transparent front fixed therein, a transparent 20 panel between said transparent fronts, a casing secured to said front, and means within said casing for causing light to pass through said panel.
12. In a sign, a luminous tube, a casing having a transparent front adapted to position said tube therein and act as a front support therefor, a reflector partially supported on said tube, said casing having a rearwardly extending part serving to further and completely support said 30 tube and reflector, a transformer mounted on said casing and having its secondary connected to said tube and entirely enclosed by said casing, and a flexible connection extending outwardly through the wall of said casing and connected 35 at its inner end to a winding on said transformer therein.
13. In a sign, a luminous tube, a casing having a transparent front adapted to position said tube therein and act as a front support, a reflector partially supported on said tube, said casing having a rearwardly extending part serving to further and completely support said tube and reflector, a transformer supported in a rearwardly extended portion of said casing, and a 40 transparent panel overlying said transparent front and removably supported on said casing.
14. The sign as claimed in claim 13 wherein a resilient support is provided bearing against the tube and reflector, and said support being 45 mounted upon an interior wall of the casing and enclosed thereby.

HARRY R. VAN DEVENTER.
